US00D786824S

(12) **United States Design Patent** (10) **Patent No.:** **US D786,824 S**
(45) **Date of Patent:** **** May 16, 2017**

(54) **HEADPHONE**

(71) Applicant: **Ooh Mommy LLC**, Manhasset, NY (US)

(72) Inventor: **Jason L. Hembrey**, Manhasset, NY (US)

(73) Assignee: **Ooh Mommy LLC**, Manhasset, NY (US)

(**) Term: **15 Years**

(21) Appl. No.: **29/573,090**

(22) Filed: **Aug. 2, 2016**

(51) LOC (10) Cl. **14-01**

(52) U.S. Cl.

USPC **D14/205**

(58) **Field of Classification Search**

(57) **CLAIM**

The ornamental design for headphone, as shown and described.

DESCRIPTION

FIG. 1 is a perspective view of one embodiment of headphone showing my new design;

FIG. 2 is a front elevation view thereof;

FIG. 3 is a rear elevation view thereof;

FIG. 4 is a right side elevation view thereof, the left side elevation view being a mirror-image thereof;

FIG. 5 is a right side elevation view thereof with a section line 6-6 through a portion thereof;

FIG. 6 is a section taken through line 6-6 of FIG. 5;

FIG. 7 is a top view thereof;

FIG. 8 is a bottom view thereof;

FIG. 9 is a front view in an alternate folding configuration;

FIG. 10 is a perspective view of an alternative embodiment of headphone showing my new design;

FIG. 11 is a front elevation view thereof;

FIG. 12 is a rear elevation view thereof;

FIG. 13 is a right side elevation view thereof, the left side elevation view being a mirror-image thereof;

FIG. 14 is a right side elevation view thereof with a section line 15-15 through a portion thereof;

FIG. 15 is a section taken through line 15-15 of FIG. 14;

FIG. 16 is a top view thereof;

FIG. 17 is a bottom view thereof; and,

FIG. 18 is a front view in an alternate folding configuration. The broken lines depict environment that forms no part of the claimed design.
